OTIS T. GREGG, OF HACKENSACK, NEW JERSEY, ASSIGNOR TO THE GREGG COMPANY, LIMITED, OF NEW YORK, N. Y., A CORPORATION OF NEW YORK

BOX CAR

Application filed February 28, 1928. Serial No. 257,565.

The present invention relates to box cars, and more particularly to the superstructure of such cars, the object thereof being to provide a car which is both strong and well-braced and at the same time is flexible so that it can accommodate itself to the irregularities of an uneven track to thereby reduce to a minimum the liability to derailment.

Railway cars are kept upon the track by the downward pressure of their wheels upon the rails. Hence, on the uneven tracks of those railroads in this country, and especially of many of the standard and narrow gauge roads in certain foreign countries, the revenues of which are insufficient to provide for proper track maintenance, it is most desirable that the wheel loads of the cars be kept as uniform as possible since disproportional loads on the different wheels are a major cause of derailments.

The car underframe of four-wheel cars is supported on two axles, located towards the ends of the car, by four identical journals. Consequently, in passing over an uneven track one end of an axle will rise or fall with respect to its other end with the result that, unless the underframe is flexible and can twist so as to conform to the irregularities of the track, the four sets of springs associated with the four journals will be compressed to different degrees, and therefore the load transmitted therethrough to two of the four wheels, at diagonally opposite corners of the car, will be insufficient to hold these wheels firmly upon the rails. And the same is true of eight-wheel cars, where the underframe is supported upon two trucks each with two axles joined more or less flexibly together so that the wheels may yield to track irregularities. In these cars the weight of the car is normally supported only upon a bearing at the center of each truck, which bearing reflects the resultant or average height of the four wheels thereof; but, to balance the underframe upon the trucks, side bearings are pro-

vided which normally have a slight clearance and, as each reflects the average height of the two wheels on its side of the truck, it follows that, as in four-wheel cars, the underframe must twist with the irregularities in the track if the wheel loads are to be kept substantially uniform. The slight reduction in the required distortion of the underframe of the eight-wheel cars, due to the clearance between the side bearings, is as a rule more than offset by their greater length.

The underframes of cars, both four- and eight-wheel cars, are easily and customarily so designed that when riveted up complete they will have sufficient flexibility to accommodate themselves to uneven track conditions without greatly disproportioning the wheel loads. Little difficulty therefore is experienced in the case of flat or platform cars, but where cars have a superstructure built upon their underframes, as in hopper cars, gondolas, box cars, etc., the superstructure must also be made flexible as otherwise the underframe will be kept from yielding, with the resultant unequal loading of the car wheels on an uneven track.

To provide such a flexible superstructure in box cars, my present invention is directed to a simple and novel roof construction which consists, broadly stated, in a series of transverse roof plates pivotally joined to the sides, or to one side, of the car and so overlapping one another as to both allow a relative movement of the plates and form water-shedding joints. The flexibility or, rather, deformability, of the roof permits the balance of the superstructure, especially the side walls, to be made of the usual strength and well braced as required to resist the many strains of loads, bumping of cars when coupling, derailments, etc., by giving to the superstructure as a whole a flexibility which enables it to yield in conformity with the desired twistings of the underframe.

Several practical embodiments of the in-

vention are shown, by way of illustration and not of limitation, in the accompanying drawings, in which—

Figs. 1, 2 and 3 are, respectively, end, side, 5 and top or plan views of an eight-wheel box car equipped with the new flexible roof, showing the shape assumed by the superstructure when distorted by a rise in the rail under the wheels on one side of one of its trucks; 10 Fig. 4 is a view of the upper part of the car superstructure, in transverse section, showing the sides of the car with their two eaves angles and a roof plate pivotally attached thereto; and Figs. 5, 6, 7, 8, 9 and 10 are similar views, on an enlarged scale, of broken portions of the upper part of the car superstructure, showing, in side elevation, the flexible roof as formed in different ways with plates or sheets of various forms. 15

Referring first to Figs. 1 to 4 of the drawings, *a b c d* indicate the corners at one end of the car, the forward end for example, and *a' b' c' d'* indicate the corresponding corners at the rear end of the car. The corners at the near and far sides of the car will therefore be indicated by *a' a, c' c* and *b' b, d' d*, respectively. 20

The car underframe, comprising the side sills 11 11' and the end sills 12 12', is mounted 25 in the usual manner upon forward and rear trucks 13 13' the wheels of which rest upon rails 14 14'.

The superstructure of the car is framed at its sides and ends by the usual corner stakes 30 15 and, on each side, by door stakes 16, intermediate stakes 17 and diagonal stakes 18, 19, and eaves angle 20, the corner and side stakes being fixed as usual at their lower ends to the side sill and at the top to the eaves angle, 35 and at each end by end stakes 21, fixed to the end sill, and end plate 22 fixed to the top of the end and adjoining corner stakes. This frame is closed by the usual side sheathings 23 and end sheathings 24.

The deformable roof consists, essentially, 40 of a series of transverse metallic plates 25, galvanized steel sheets for instance, which are bent centrally on a curve as shown or at an angle, or may be convexly arched in a continuous curve, so as to be highest at the transverse center of the car to thus enable them to 45 shed water to both sides thereof. These plates overlap one another and are so shaped along their overlapping edges as to provide 50 a loose interlock or joint, at 26, which serves to keep out the water while allowing to some extent a relative movement of the plates both laterally and longitudinally; and each plate is pivotally attached to and secured in place 55 upon the outwardly inclined flange of the eaves angles by a single bolt 28 at one, or preferably at each, of its two ends. When bolted at one end only, the plates will be held 60 in place at their other ends by the interlocks 65 but the sides of the car should be connected

together by the carlines commonly used in connection with corrugated-sheet roofs, whereas, if bolted at each end, the carlines can be omitted. The outward slope of the flanges of the eaves angles, which should 70 conform more or less closely to the slope of the roof plates, serves to carry off any water which may work through the bolt holes in the plates and hence allows of the direct bolting of these plates to the eaves angles. 75

A roof constructed as described functions as follows: It will be understood that on an uneven track the trucks and/or axles at the opposite ends of a car will be tilted over first to one side and then to the other and so out of level with each other. Whatever the twistings of the track and tilting of the car trucks, however, such twisting will be reflected, by reason of the deformable character of the roof, in a corresponding twist or flexure of the underframe and the entire superstructure of the car. For example, as here shown, the rail 14 is raised beneath the wheels on the near side of the rear truck 13' thus tilting this truck over and out of level with the horizontal forward truck, with the result that the entire rear end of the car is tilted up and over to its far side, about the rail 14' as an axis—a movement which twists the underframe and the two sides of the car, which may be rigidly braced as usual by diagonal stakes, with an accompanying deformation of the roof which through the pivotal action of its plates is shifted from its normal rectangular to a more or less diamond-shaped form, the ends of the roof plates presenting, at each side of the car, a saw-tooth arrangement. Such a result is entirely impossible with a rigid roof, since the unyielding character of the roof will effectually prevent the flexing of the sides of the car and through them a flexing of the underframe. 90

It is to be noted that as the roof plates pivot in the deformation of the roof, their overlapping edges shift not only lengthwise thereof but to some extent either to or from each other as the case may be. Hence, the jointure between the plates should provide the clearance necessary for such movement. Different forms of plates can be joined in various ways to give the required clearance, a few examples of which are here illustrated and will now be described. 100

In Fig. 5, which may be regarded as showing on an enlarged scale the roof structure shown in the preceding figures, the roof plates or sections 25, all alike and each pivoted centrally thereof to the eaves angle by a bolt 28, are formed from plain sheets which are shaped along their edges to provide a single downwardly opening corrugation or trough of small radius at one and of larger radius at the other edge, the large corrugation 26 of one plate loosely covering the smaller corrugation 27 of an adjacent 115 120 125 130

plate so as to leave clearances x y which will permit the plates to shift somewhat either towards or from each other.

As modified in Fig. 6, the roof plates 65, 5 also made from plain sheets, are shaped angularly to provide at one edge a downwardly opening corrugation 66 of rectangular section and at the other edge an upwardly projecting flange 67, and a single special 10 plate or section 65', which will usually be placed at the longitudinal center of the car, is provided with a downwardly opening rectangular corrugation 66 at both of its edges. Here, the plates 65 are reversely positioned 15 on the opposite sides of the special plate 65', the flanged edge of one plate being covered by one of the corrugations of the plate 65' and its flanged edge in turn covered by the corrugation of the next adjoining plate. The clearances x y permit the necessary relative movement of the joined plates. By the 20 location of the pivot bolts of the plates 65 close to the overlapping corrugated edge, as shown, this edge of the plate and with it the 25 underlapping flanged edge of the adjoining plate will be held firmly down upon the eaves angles.

In Fig. 7 the roof structure shown in Fig. 5 is modified merely to the extent that every 30 other plate 75 has a corrugation 76 of the larger radius at both of its edges while the intermediate plates 75' have at each edge a corrugation 77' of the smaller radius, the two structures functioning in substantially 35 the same way.

In the roof of Fig. 8 standard corrugated galvanized roof sheets are used for the plates, being so placed that the outer corrugation 86 of one plate overlaps and covers 40 the adjoining outer corrugation 87 of the next plate. It is to be noted that in the construction here illustrated, which is both extremely simple and cheap, no clearances are provided in the joints. The movement 45 of the plates to and from each other in pivoting is, however, permitted by the upward springing of the overlapping corrugation under the wedge action of the sloping sides of the underlapping corrugation. The 50 springiness of the overlapping upper corrugation can be increased or diminished by shifting the pivot bolt, here shown as located at the bottom of the central corrugation of each plate, away from or towards this 55 edge of the plate, but the firmness with which both of the joined plates are held upon the eaves angles will be inversely affected thereby. The relative desirability of the greater flexibility or of the greater firmness 60 in the roof will depend largely upon the conditions of the track on which the car is to be used. Joint clearances, if desired, can be obtained by cutting back the edge of the underlapping corrugation and reshaping it 65 to a somewhat smaller radius.

In the modification shown in Fig. 9, the roof plates 95 95' are also more or less standard corrugated sheets but the alternate plates 95' are here turned bottom side up, the arrangement being such that the downwardly projecting outer half 96 of the marginal corrugations of a plate 95 will on each side thereof overlap the reversed outer half 97 of the marginal corrugation of the adjoining plate 95'. 70 75

As further modified in Fig. 10, the car roof combines a series of the corrugated plates 95' with an alternating series of plates 65', 75, the squared or curved marginal corrugations of the latter plates overlapping on each of 80 their sides the upwardly projecting outer half of a marginal corrugation of a plate 95' and providing clearances x y for the relative movement of the overlapped portions.

It will of course be understood that the roof structure may be still further modified in its several details, within the scope of the appended claims, without departing from the principle or sacrificing the advantages of 85 the invention. 90

What I claim as new, and desire to secure by Letters Patent, is—

1. In a box car, the combination, with an underframe and framed ends and sides, of a deformable roof comprising a series of 95 transverse plates sloping from the center outwardly and downwardly and extending out over and past the side of the car, the said plates being upset and overlapped throughout at their adjoining edges in order to form 100 loose water-shedding joints and each plate being pivotally attached at each end to the side of the car by a single bolt. 100

2. In a box car, the combination, with an underframe and framed ends and sides, including stakes, of eaves angles attached to the upper ends of the side stakes on each side and having each an outwardly inclined top flange and a deformable roof comprising a series of transverse roof plates sloping from the center outwardly and downwardly and extending out over and beyond the eaves angle on each side and each pivotally secured at each end directly to the eaves angle by a single bolt, the edges of the adjoining plates being upset and overlapped throughout in manner to form a loose watershedding joint. 110 115

3. In a box car, a deformable roof comprising a series of relatively narrow transverse roof plates sloping from the center outwardly and downwardly and extending over and beyond the side walls of the car and each pivotally attached to each side wall, the said plates having their adjacent edges upset and overlapped throughout to form loose water-shedding joints and constituting the sole connection between the top of the side walls intermediate the ends of the car. 120 125

4. A box car comprising an underframe, framed ends and sides including stakes, and 130

a deformable roof, each side of the car having attached to the upper ends of its stakes an eaves angle with outwardly inclined top flange and the deformable roof comprising 5 a series of transverse corrugated sheets arranged with the marginal corrugation of one sheet overlapping the marginal corrugation of an adjoining sheet in manner to form a loose water-shedding joint and each sheet 10 pivotally attached at each end directly to the flange of an eaves angle by a single bolt and constituting the only top connection between the sides of the car intermediate its ends.

OTIS T. GREGG.
